UNITED STATES PATENT OFFICE.

GEORGE E. WHITNEY, OF YONKERS, NEW YORK, ASSIGNOR TO THE INTERNATIONAL PAVEMENT COMPANY, OF HARTFORD, CONNECTICUT, A CORPORATION OF CONNECTICUT.

MIXER.

1,109,725.

Specification of Letters Patent.

Patented Sept. 8, 1914.

Application filed November 27, 1908. Serial No. 464,676.

To all whom it may concern:

Be it known that I, GEORGE E. WHITNEY, a citizen of the United States, residing at Yonkers, in the county of Westchester, State 5 of New York, have invented an Improvement in Mixers, of which the following description, in connection with the accompanying drawings, is a specification, like letters on the drawings representing like parts.

10 This invention relates to means for distributing and mixing finely divided material. While it may be of general application, it is primarily intended for use in the manufacture of compressed asphalt paving 15 blocks and tiles ordinarily composed of a body material of crushed or pulverized stone united by an asphaltic or equivalent cement or binder.

In order that the principles of my invention may be readily understood, I have disclosed a single type or embodiment thereof in the accompanying drawings, wherein—

Figure 1 is a plan view of an apparatus embodying my invention; Fig. 2 is a vertical 25 section upon the line 2—2 of Fig. 1; Fig. 3 is a detail illustrating one means of supporting the mixer frames; and Fig. 4 represents a modified form of my invention.

The body material and especially the 30 finely divided material customarily employed in the manufacture of asphaltum blocks and tiles varies to a considerable extent in fineness, but this is not objectionable, in fact is desirable provided the distribution 35 of the coarse and fine material is uniform at all times. This material is usually discharged into bins or receptacles from which it is drawn for use. The material as discharged, for instance into the bins, heaps up 40 into conical form beneath the inlet, the finer material forming the center of the conical mass and the coarser material running down the sides in all directions and to the sides of the bins or piles. This results in a practical 45 separation of the finer and coarser material, so that the material drawn from these bins or piles varies greatly, running either fine or coarse according to the part of the bin or pile that for the moment supplies 50 the material. The inevitable result of this condition is that the asphaltum blocks and tiles made from this body material are composed, some of coarse and some of fine material, and hence do not wear similarly and 55 are not of the same strength as blocks where-

in the material of varying grades of fineness is evenly distributed throughout.

The object of my invention is to prevent the separation of coarse and fine material and the handling thereof.

Referring to the drawings, the chute through which the material is delivered into the bins is represented at 1 and is preferably elongated, the bin or receptacle being indicated at 2. Beneath the mouth of the chute 60 1, I place a distributing member or shelf 3, preferably flat in cross-section. It may, however, be triangular in certain cases, and is so shown in this instance. The apex or ridge 4 of the shelf is preferably alined centrally of the chute 1, so that the material discharged from the chute is deflected in opposite deviations down the inclined faces 5, 6 of the shelf, or of the pile, if a flat shelf is used. It is apparent that if the shelf 3 be 70 substantially flat the material is permitted to accumulate thereon in heaps, down the sides of which the coarser material slips in the manner already described.

Beneath the shelf 3 I preferably provide 80 one or more other distributing shelves of suitable character, and preferably flat if the shelf 3 be flat, or triangular if that be triangular. In the present embodiment of my invention I have represented three other 85 shelves mounted in frames, numbered respectively 7, 8 and 9. The shelves of the various series are herein arranged in echelon. The shelves 10 of the frame 7 receive the material from the shelf 3 and in turn 90 divide and deflect it in opposite directions in a series of streams upon the shelves 13 of the frame 8, from which it is delivered in an increased number of divided streams to the shelves 14 of the frame 9, which delivers 95 it in a still greater number of divided streams to and thoroughly distributes it over the area of the bin 2. By thus interrupting the flow of the material, there is no opportunity for the coarser and finer particles to 100 become segregated, and by so placing the shelves as to divide the columns of material discharged upon them and deviating the divided columns in different directions, herein upon staggered shelves beneath, a 105 uniform distribution of unseparated and uniform material is obtained over a very large bin or other area.

Dependent upon the height of the column of the material delivered through the 110

chute 1, the material flows with more or less force down the sides 5 and 6 of the frame 3. If it flows with less than the normal force from the chute 1, it will fall 5 within the apices of the shelves or bars 10, and hence would be distributed only by the inner faces thereof, unless means are provided to prevent this. If, however, the material should flow with more than the normal force, it would be discharged upon the 10 apices of the said bars 10, and hence would be distributed only by the outer sloping faces thereof. The result in either case would be the unequal distribution of the material by the shelves or bars of the several frames. To prevent this unequal distribution, due to unequal velocity of flow of the material, I impart a relative movement to the chute 1 and the shelves on the 15 frames 7, 8 and 9. Preferably, I move the frames to and fro beneath the shelf 3 so as to vary constantly the positions of the shelves relatively to each other. For example, as the frame 7 is moved to the right, its left-hand shelf 10 is brought more directly beneath the left-hand edge of the shelf 3 to catch the material if it be at the moment flowing below the normal velocity while, at the same time, the right-hand shelf 10 is 20 moved farther out to catch material that may be flowing above the normal velocity. In other cases if the machine overshoots or undershoots the shelf 10 at either side of the shelf 3, it will be caught upon the 25 shelves next beneath, which preferably are, at the same time, moved in an opposite direction to the opposite extreme positions. Thus by maintaining the several series of shelves constantly and oppositely in reciprocation, their positions are constantly changed 30 relative to each other, presenting at one instant positions to receive material flowing at high velocity, and at the next instant material flowing at lower velocities, the material that overshoots or undershoots one shelf being invariably caught and held by a shelf beneath. The result of this is in effect to 35 present a plurality of series of shelves which, at all times, are capable of acting upon and properly controlling the flowing material, whether the latter flow at a constant velocity or at variable velocities. Any suitable means may be employed for shifting these shelves. Herein I have represented the frames 7, 8 and 9 as suspended by 40 links 19, thus permitting the lateral shifting by any suitable mechanism or by hand. For the purpose I have represented rods 21 connected to the frames 7, 8 and 9 and having outer transversely slotted heads 22 receiving crank pins upon worm gears 23 meshing with which are worms 24 upon a vertical shaft 25 mounted in suitable bear-

ings and driven from any suitable source. The operating mechanism for the links 21 is 65 preferably inclosed by a suitable casing 26 having holes for the passage of the rods and preferably flexible packing diaphragms 27 preventing the contact of the pulverized and powdered material with the worms and worm wheels or other operating mechanism. Preferably the crank pin 22 for the frame 8 is 70 oppositely positioned with respect to the crank pins 7 and 9, so that the frames are 75 oscillated or shifted in opposite directions. 75

The several frames may be of any suitable shape or contour. In Fig. 4 I have represented a circular frame 28 in lieu, for example, of the frame 8, Fig. 2, and receiving the material from a ring-like top shelf above and discharging it upon annular frames beneath, from which it may be discharged, if desired, to other suitable frames. Preferably these frames are also relatively 80 shifted or gyrated with respect to each other. Herein for the purpose I have represented the frame 28 as gyrated by crank mechanism 29. This may be accomplished 85 in any suitable manner as, for example, by connecting the crank mechanism by links 30 90 sliding and oscillating in suitably mounted sleeves.

Having thus described one type or embodiment of my invention, I desire it to be understood that although specific terms are employed they are used in a generic and descriptive sense and not for purposes of limitation, the scope of the invention being set forth in the following claims.

Claims:

1. A mixer comprising in combination a downwardly increasing series of deflectors and means for moving said series relatively to each other.
2. A mixer for granular and pulverulent material comprising in combination, a plurality of interrupting shelves arranged in echelon and means to impart an oppositely substantially horizontal reciprocal movement to the adjacent parallels of said echelon.
3. A mixer comprising in combination a downwardly increasing series of deflectors and means for shifting a plurality of said series oppositely in reciprocation.
4. A mixer comprising in combination a downwardly increasing horizontally arranged series of shelves and means to impart oppositely reciprocal horizontal movements to adjacent series of said shelves.

In testimony whereof, I have signed my name to this specification, in the presence of two subscribing witnesses.

GEO. E. WHITNEY.
